UNITED STATES PATENT OFFICE

JACOB KOHUT, OF ST. LOUIS, MISSOURI

DESIGN FOR A COMBINED LAMP AND CLOCK OR SIMILAR ARTICLE

Application filed March 9, 1931. Serial No. 39,008. Term of patent 14 years.

To all whom it may concern:

Be it known that I, JACOB KOHUT, a citizen of the United States, residing at the city of St. Louis, State of Missouri, have invented a certain new, original, and ornamental Design for a Combined Lamp and Clock or Similar Article, of which the following is a specification, reference being made to the accompanying drawings, forming a part thereof, in which—

Figure 3 is a plan view, of a combined lamp and clock or similar article embodying my new design.

I claim—

The ornamental design for a combined lamp and clock or similar article substantially as shown.

JACOB KOHUT.
